UNITED STATES PATENT OFFICE.

ANDREW H. CANDEE, OF PITTSBURGH, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,427,356.

Specification of Letters Patent. Patented Aug. 29, 1922.

Application filed October 6, 1919. Serial No. 328,842.

To all whom it may concern:

Be it known that I, ANDREW H. CANDEE, a citizen of the United States, and a resident of Pittsburgh, in the county of Allegheny and State of Pennsylvania, have invented a new and useful Improvement in Systems of Control, of which the following is a specification.

My invention relates to systems of control for dynamo-electric machines, and it has particular relation to main-circuit connections for a two-motor railway equipment, or the like.

One object of my invention is to provide a relatively simple and inexpensive system of connections whereby uniform operation of a plurality of railway motors throughout series-parallel connections thereof may be effected, even though unequal steps of resistance are provided.

More specifically stated, it is the object of my invention to provide an accelerating resistor that is connected intermediate two driving motors and is excluded from circuit in unequal steps during series connection of the motors, whereas, under parallel operating conditions of the motors, the unequal sections of the resistor are connected in parallel relation and the connection of the resistor to the supply circuit is such as to insure equal voltages upon the two motors in their initial parallel-circuit relation.

My invention may best be understood by reference to the accompanying drawing, wherein

Figure 1 is a diagrammatic view of the main circuits of a system of control organized in accordance with my present invention; and

Fig. 2 is a simplified diagrammatic view of an auxiliary controlling system for operating the various switches in the preferred order that is indicated in the sequence chart, Fig. 3, of well-known form.

Referring to Fig. 1, the system here shown comprises suitable supply-circuit conductors Trolley and Ground; a plurality of driving motors respectively having commutator-type armatures A1 and A2 and series field windings F1 and F2; an accelerating resistor 1 having unequal portions 1a and 1b; and a plurality of governing switches for the motors: a line switch LS1 for series operation, a second line switch LS2 for parallel operation, another parallel-connect-

ing switch G and two resistor short-circuiting switches R1 and R2.

The switch R1 is connected across the larger section 1a of the accelerating resistor 1, while the switch R2 is connected across the terminals of the entire resistor. The switch LS2 connects the Trolley to the junction-point of the resistor sections 1a and 1b. Switch LS1 serves to connect the trolley with the left-hand terminal of the motor having the armature A1, while switch G is connected between the same terminal and Ground.

In Fig. 2, I have shown a simple master controller for directing energy from a battery B, or other suitable source, to the actuating coils of the respective switches in the preferred order, as indicated in Fig. 3.

Assuming that it is desired to effect acceleration of the motors, the master controller MC is actuated to its initial operative position *a* whereupon a circuit is established from one terminal of the battery B, through conductor 2, control fingers 3 and 4, which are bridged by contact segment 5 of the master controller, conductor 6, the actuating coil of line switch LS1 and conductor 6a to the negative battery terminal. The line switch LS1 is thus closed, as indicated in step *a* of the sequence chart.

Under such conditions, a main circuit is established from the trolley through conductor 7, line switch LS1, junction-point 8, conductor 9, field winding F1, armature A1, junction-point 10, the entire accelerating resistor 1, junction-point 11, armature A2 and field winding F2 to Ground. The driving motors are thus connected in series relation, with the accelerating resistor 1 located between them, across the supply circuit.

Movement of the master controller to position *b* effects engagement of the contact segment 5 with control finger 12, whence circuit is completed through conductor 13 and the actuating coil of the switch R1 to the negative conductor 6a. The larger resistor section 1a is thus short-circuited to effect a predetermined degree of acceleration of the driving motors.

In position *c* of the master controller, a new circuit is established from the contact segment 5 through control finger 15, con-

ductor 16 and the actuating coil of the switch R2. The remaining or smaller resistor section 1b is thus also excluded from circuit although, as previously stated, the 5 switch R2 is connected across the entire resistor 1.

To effect transition of the motors from series to parallel relation, the master controller is moved to position *d*, whereupon, 10 at first, control finger 12 breaks contact with controller segment 5, to cause the switch R1 to open. A circuit is next established from the contact segment 5, through control finger 17 and conductor 18 to the actuating 15 coil of the line switch LS2, and subsequently the control finger 4 becomes disengaged from the contact segment 5 to effect opening of the line switch LS1. Just before the master controller reaches its position *d*, 20 a new circuit is established from the contact segment 5 through control finger 20 and conductor 21 to the actuating coil of the switch G.

Consequently, in the first parallel position *d* of the master controller, the main 25 circuits may be traced as follows: from the trolley through conductor 19, line switch LS2, junction-point 14 of the resistor sections 1a and 1b, where the circuit divides 30 and passes through parallel circuits including the two resistor sections and the switch R2. One circuit is continued from the junction-point 10, through armature A1, field winding F1, conductor 9, junction-point 8 35 and switch G to Ground, while a second circuit is completed from junction-point 11 through armature A2 and field winding F2 to Ground.

By reason of the fact that switch R2 remains 40 closed during transition and parallel operation of the motors, it follows that the amount of resistance inserted in circuit with each of the motors is the same, even though the resistor sections 1a and 1b are unequal, 45 which is desirable for purposes of series acceleration.

Furthermore, the line switch LS2 need not be connected to the junction-point 14, but may be joined to any desired point in the 50 resistor 1, whereby the effective resistance in circuit with the parallel-related motors may be varied as desired.

In position *e*, contact segment 5 again engages control finger 12, whereby the switch 55 R1 is once more closed to complete the short-circuit of the resistor 1 and thus accelerate the motors to full-parallel relation.

It will be understood that the principles 60 of my invention, whereby unequal resistance steps may be employed during series operation of the motors, and equal resistance values are included in circuit with the motors during parallel acceleration, may be readily applied to systems involving the use of more 65 than two resistor short-circuiting switches.

In this way, the proper proportioning of the resistance steps for smooth acceleration during both series and parallel connection of the motors may be provided.

I do not wish to be restricted to the specific 70 circuit connections or arrangement of parts herein set forth, as various modifications thereof may be made without departing from the spirit and scope of my invention. I desire, therefore, that only such limitations 75 shall be imposed upon my invention as are indicated in the appended claims.

I claim as my invention:

1. In a system of control, the combination 80 with a plurality of dynamo-electric machines and an accelerating resistor, of means comprising five switches for effecting series-parallel operation of the machines including unequal exclusions of resistor sections during series operation and equal distribution 85 of the resistor in the motor circuits for parallel operation.

2. In a system of control, the combination 90 with a plurality of dynamo-electric machines and an accelerating resistor permanently connected between them, of switching means for producing unequal resistance steps during series operation and equal voltage distribution for parallel operation.

3. In a system of control, the combination 95 with a plurality of dynamo-electric machines and an accelerating resistor permanently connected between them, of two individual switching means respectively adapted to be connected across a part and the whole of said resistor, and a line switch adapted to be connected to an intermediate point of the resistor.

4. In a system of control, the combination 105 with a plurality of dynamo-electric machines and an accelerating resistor permanently connected between them, a switch adapted to be connected across a section of said resistor, a second switch adapted to be connected across the whole of the resistor, and a line switch adapted to be connected to an intermediate point of the resistor, said second switch and said line switch being closed during parallel operation of the motors.

5. In a system of control, the combination 115 with a plurality of dynamo-electric machines and an accelerating resistor permanently connected between them, of a switch for short-circuiting a major portion of said resistor and a second switch for subsequently 120 short-circuiting the whole resistor during series operation of the motors, and a line switch connected to an intermediate point of said resistor during parallel operation of the motors, said second switch remaining closed during transition and parallel operation of the motors to balance the voltages applied thereto.

6. The method of operating a plurality of 130 motors in conjunction with a supply circuit

and an accelerating resistor which consists in excluding said resistor from circuit in unequal steps during series operation of the motors, and parallel-circuiting the resistor to produce equal voltage distribution from the supply circuit to the motors during parallel operation thereof.

7. The method of operating a plurality of motors in conjunction with a supply circuit and an accelerating resistor which consists

in excluding said resistor from circuit in unequal steps during series operation of the motors, and connecting a supply-circuit conductor to an intermediate point of said resistor and joining the ends thereof during parallel operation of the motors. 15

In testimony whereof, I have hereunto subscribed my name this 30th day of Sept. 1919.

ANDREW H. CANDEE.
